UNITED STATES PATENT OFFICE.

ALBERT KRAUTH, OF HAMILTON, OHIO; FRITZ G. DIESBACH ADMINISTRATOR OF
SAID ALBERT KRAUTH, DECEASED.

MANIFOLDING-MACHINE.

1,338,140.

Specification of Letters Patent. Patented Apr. 27, 1920.

Application filed October 30, 1915, Serial No. 58,900. Renewed March 13, 1920. Serial No. 365,663.

To all whom it may concern:

Be it known that I, ALBERT KRAUTH, a citizen of the United States, and residing at Hamilton, in the county of Butler and State of Ohio, have invented a new and useful Improvement in Manifolding-Machines, of which the following specification is a full disclosure.

The invention herein is primarily directed to devices for engaging through the perforations in the several superposed strips of paper upon a writing-table, for exact registration and alinement of the printed forms on the several strips, for holding the strips at opposite ends of the table and tautly stretching the paper upon the table, and for regulating the distances of successive advancement or withdrawal of the paper.

It is particularly adapted to manifolding machines in which usually several webs of paper in a superposed relation are supported upon and drawn over a writing table for manifolding record entries. The webs each contain preprinted forms and are withdrawn from the machine as the forms are used and severed from the strip or web.

The webs or strips of paper are provided with perforations, usually punched through the paper at the head of each form printed on the strip, as file holes for each form length when severed from the strip. The perforations, for the forms of the strip, are arranged in rows or longitudinal alinement with the distance between the perforations at the head of one printed form and those at the head of a second successive form, regulating the distance of successive advancements of the strip of paper, limiting the withdrawal to a full form length and leaving the successive form of a strip in proper position, and as means for securely holding the strip at opposite ends of the writing-table tautly on the table, and the forms of the several superposed strips upon the writing-table in registration and alinement with each other.

An object of the invention is to provide means located at the forward end of the writing table to engage the paper through apertures in registry with said means for stopping or limiting the paper withdrawal or regulating the distances of the successive advancements of the strip or superposed strips together with devices for engaging through registering apertures located at the

rear end of the table and coöperating with the devices engaging the paper at the forward end of the writing table for confining the paper and maintaining the several superposed paper portions over the table in registration and alinement with each other.

Various other features and objects of the invention will be more fully disclosed by the accompanying drawings and the description thereof forming a part of this specification, and in such drawings like characters of reference denote corresponding parts throughout the several views, of which:

Figure 1 is a central vertical section of a manifolding machine of a type known to the trade as a pull-out machine, from which the paper is manually withdrawn for a determined length and severed across a tearing blade at the delivery end of the machine. Fig. 2 is a top plan view of the machine with the margin frame omitted. Fig. 3 is an inside bottom plan view with the base removed to illustrate the parts mounted upon the underside of the writing table. Fig. 4 is an enlarged section on line 4-4, Fig. 2, of the upper portion of the machine and principally through the writing table. Fig. 5 is an enlarged section on line 5-5, Fig. 3. Fig. 6 is a top plan view, on a reduced scale, of a portion of the web of perforated paper used in the machine herein described.

The invention herein is illustrated as primarily combined with a type of machine in which the paper is manually withdrawn, as representing the most simple type, but it is obvious that the invention is applicable to various other types of manifolding machines providing paper feeding mechanism for withdrawing the paper and therefore I do not necessarily wish to be confined to the type of machine illustrated.

The invention is also somewhat related to the inventions contained and made the subject-matter of a prior patent issued to me, Reissue No. 14,189, dated August 29, 1916, which discloses a member yieldingly urged toward a face of the paper adapted to engage through a registering aperture in the paper during its withdrawal from the machine to intercept the paper withdrawal.

Referring to the drawings, 1 indicates the base of the machine, 2, 3, side frames providing a casing for the rolls of paper 4, three rolls of paper being shown, but their

number being optional depending upon the size and use for which the machine is intended. The side frames are shown as of sectional form, comprising a pair of forward sections fixed to the base and a pair of rear sections as a unit fulcrumed upon the forward sections of the side frames. The rear sections are connected by a writing table 5, and as a unit may be swung upwardly for inserting and removing the rolls of paper. The rolls of paper are shown as journaled between opposing yielding hold-ers fixed to the side frames.

At the forward end of the writing table 15 5, I provide a tearing blade 6 which extends across the writing table. The tearing blade has arms extending from its opposite ends and pivoted to the side frames for swinging the blade above the table and rendering 20 accessible the end of the paper beneath the blade. An arm 8 projects rearwardly from the tearing blade providing hand-hold means for swinging the tearing blade. The strips from each roll are respectively fed 25 over the guiding rollers 9, at the rear upper edge of the casing and from the rollers forwardly over the writing table to the tearing blade. These parts are common to all mani-folding devices. A margin frame, not 30 shown, is usually provided to marginally surround the writing table and cover the guide rollers at the rear upper portion of the machine. The machine along one side is also provided with a carbon holder or re-35 ceptacle for holding a supply roll of carbon paper, which is fed across the writing table between the several strips fed from the rolls 4. The strips of paper are pro-40 vided with spaced apertures longitudinally dividing the strip into sheet lengths or form sizes.

The apertures or perforations are spaced laterally apart in a definite and invariable relation with the printed matter of each form 45 and are usually located at the head of each form to serve as filing holes when the form is severed from the strip. Each strip is composed of a succession of independently related forms, each form consisting of 50 printed matter and two laterally spaced holes. In the machine several of these strips are passed, in a superposed relation, over a writing-table, until they are stopped by 55 depressible pins, at the forward end of the writing-table, engaging upwardly through the perforations of the paper, with the effect that all of the forms of the several strips are stopped in the same relation to the pins. Any form of one strip, in advance of a rela-60 tive form of a second or third strip, will be assisted first and the others will not be arrested until they have moved up into alinement with it. Depressible pins located at the rear end of the writing-table, having a 65 yielding forward motion, are arranged to

engage through the apertures or perforations of a successive form of each of the several strips and slightly in advance of the engagement of the pins at the forward end of the table, so that the rear pins are drawn forward with the strip against the tension of the spring to exert a rearward pull on the forms when engaged with the forward pins, drawing the forms tautly over the writing-table in registration and lateral 75 alinement with each other. The perforations, therefore, provide means of regulating the distances of the successive advancements of the strips and for limiting the withdrawal to the distances between the 80 perforations.

The forward end of the writing table is notched as at 9', Fig. 2, to expose the end of the paper so that it may be grasped for paper withdrawal, and also to enable the 85 tension blade 10 fulcrumed upon the cross-bar 11 connected to the side frames to en-gage against the cross-bar or plate 12, sup-ported over the writing table. The ten-sion blade serves as a brake against any re-actionary motion of the paper. The tension blade is operated with the tearing blade, so that when the tearing blade is in its nor-mal position the tension blade is released 90 and free to permit the pin carried by the 95 blade to engage through an aperture in the paper when brought into registration. The tension blade is yieldingly urged toward the cross-bar by means of a spring 13, which has its ends looped around and engaged 100 with the cross-bar 11, and an intermediate loop which engages the tension blade. The arms 14, which support the tearing blade, are fixed to a rock shaft 15 journaled in the side frames and maintained under tension 105 by a spring 16 encircling the rock shaft with its ends respectively engaged with the side frame and shaft, for automatically re-turning the tearing blade to its normal posi-tion when released. The rock shaft 15 has 110 an arm 17 fixed thereto and is adapted to be connected with means for moving the paper arresting devices to a non-paper-engaging position. The arm 17 engages with a lug 18 projected from the tension blade, for 115 controlling its position with the movements of the shaft 15. Thus it will be seen that when the arm 17 moves rearwardly it will release the tension blade to permit it to en-gage the cross-bar or plate 12 binding the 120 paper and operating as a wedge-bar or pawl to prevent rearward movement of the paper. Under such control of the tension blade the paper is relieved during the major portion of a withdrawing operation.

The paper arresting mechanism is ar-ranged to operate upon the paper at the for-ward and rearward ends of the writing table, embodying devices adapted to engage through registering apertures in the paper. 130

The forward devices primarily limit the withdrawal and coöperate with the rear devices to confine superimposed lengths of paper in a taut condition over the writing 5 table, for registry and alinement purposes.

The forward arresting devices may be substantially the same as that disclosed in my aforesaid patent, comprising a pair of spring blades 19, 20 of duplicate construction to provide for one set of pins.

The blades 19, 20 are secured to the under surface of the writing table as the most convenient place. These blades 19, 20 are each intermediately secured to provide opposite 15 free ends for carrying the forward and rearward paper engaging detents. As both the blades are duplicates the detailed description will be confined to one. The forward end of, say, blade 19 has a pin 21 fixed thereto, projecting upwardly to engage through a registering aperture in the writing table and also through an aperture in the cross-bar 12 when intercepting the movement of the paper. The blades 19, 20 25 are connected by cross-bars 22, for being controlled as a unit. The pins 21 are preferably of segmental form as shown in Fig. 4, presenting a rounded or semi-circular portion toward the forward end of the machine, corresponding in radius to that of the 30 perforations in the paper. At the rear end of the blade 19 I provide a movable pin 23 having a compound motion transversely to and in the plane of the paper, whereby the 35 pin is adapted to engage through a registering aperture and move with the paper for a limited space or distance and under a rearward or retarding tension, pulling the paper rearwardly when the paper is engaged with the forward pins to aline the 40 apertures of the several strips over the forward pins and maintain the paper in a taut condition over the writing table. As a plural number of pins 23 are employed for 45 equalizing purposes, it will be noticed that they are fixed to a yoke or slide member 24 having projecting limbs slidably engaged upon the members 19 and 20. The slide member and pins are thus unitarily combined.

The rear pin 23 has a shank portion 24 engaged through a longitudinal slot 25 in the blade 19 and held in position by a cross-pin 26 projecting through the shank 24 and 55 adapted to move forwardly upon the blade 19 against the resistance of the spring 27, said spring having one end fixed or rigidly secured to the under surface of the writing table, with its opposite end engaged with 60 the shank 24. The spring 27 also serves as means for returning the pin to its normal position after its release from the paper.

The rear pins 23—23 each are of segmental or semi-circular form in cross section at their upper ends, and similar in con-

struction to the front or forward pins 21—21 with which they respectively aline, but with their circumferential portions facing opposite to the circumferential portions of the forward pins. Such segmental form of pin 70 is of advantage in engaging through the apertures of a manifold number of strips when their relative aperture registration is disturbed, as it enables the pin under such condition to enter an opening smaller than 75 the full area of opening formed by the apertures of the several strips when in registration.

Each pin supporting blade 19 exerts an upward force on its pin sufficient to move the 80 pin quickly through a registering perforation in the paper, but its pressure on the pins, when the pin is engaged against the lower surface of the paper, is not severe enough to cause any appreciable retarding influence 85 against the withdrawal of the paper. The pin 23 is adapted to engage through a longitudinal slot 28 in the writing table, and also through a slot in the cross-plate 29 fixed to the side frames in a superposed relation over the writing table. The cross-plate 29 confines the paper over the table and with the table provides a passage 90 through which the paper passes. The cross-plate prevents the paper from being raised 95 off of the table by the pins when engaged under tension against the lower surface of the paper, while the paper is being withdrawn. The slots in said bar correspond and are in alinement with the slots in the 100 writing table. The pins are depressed and disengaged from the paper when the tearing-blade is raised for a paper withdrawal operation.

An actuating bar 30 is slidably mounted 105 upon the under surface of the writing table and intermediate of the blades 19 and 20 having its forward end pivotally connected as at 31 to the arm 17 to operate therewith. The bar 30 is provided with the wedge extensions 33, 34, adapted to coöperate with the respective blade connecting bars 22 at the forward and rear pin-carrying portions of said blades 19, 20, to depress such blade ends simultaneously upon a rearward movement 110 of the actuating bar 30, to depress the pins below the surface of the writing table. A movement of the bar 30 in the opposite direction releases blades 19, 20, to enable the pins to engage a surface of the paper and 115 through a registering aperture in the paper to intercept its progress and aline and properly confine the paper upon the writing table.

In an operation of the machine after the strips have been properly loaded within the machine and over the writing table, a form length is issued or delivered from the machine by moving the tearing blade rearwardly, releasing the pins. The tearing- 120 125 130

blade is raised to enable the operator to take hold of the ends of the strips of paper and the tearing-blade is held upward with the pins depressed until the paper has been moved sufficiently to bring the perforations beyond the pins, whereupon the tearing blade is released, and the paper withdrawal can freely continue until successive sets of perforations register with the pins. In this instance the rear pins normally being spaced from the forward pins a distance greater than the spacing distance of the perforations in the paper, are the first to engage through the paper and resistingly move with the paper until the forward perforations engage with the forward pins, arresting the withdrawal, and when such delivered or issued sheet is severed across the tearing blade, the paper within the machine is free from the manual hold, enabling the rear pins to draw the paper under their retrieving tension tautly across the writing table and aline the perforations of the several strips as well as register their printing data.

Having described my invention, I claim:

1. A device of the nature disclosed combining a casing, a writing table over which a strip of paper is withdrawn, the strip having apertures longitudinally alined in a spaced relation, and a member yieldingly movable transversely to and yieldingly movable in the direction with the paper travel over the writing table, adapted to engage through a registering aperture in the paper, and under tension move with the paper when engaged therewith.

2. A device of the class described combining a frame structure including a writing-table for supporting a strip of paper, the paper having apertures longitudinally in spaced relation, a pair of depressible paper movement intercepting members spaced longitudinally of the table, each adapted to engage registering apertures in the paper over the writing-table, one of said members being movable with the paper when engaged therewith, tension means for said member exerting a force when said member is engaged with the paper in a direction counter to the direction of travel of the paper over the table, and means for controlling said members to release them from paper engagement.

3. In a device of the class described, a casing, including a writing table over which a strip of paper is drawn, the paper having apertures longitudinally in spaced relation, a vertically disposed depressible pin to engage said paper and through a registering aperture therein, said pin mounted to move with the paper when engaged through an aperture, tension means for moving said pin counter to the direction of paper feed, a rocking tearing blade for severing a strip

length of paper withdrawn from the casing, and means connecting said tearing blade and pin for unitary control thereof.

4. In a machine of the class described, a frame structure including a writing table over which a series of manifolding strips of paper are drawn, the paper provided with longitudinally spaced apertures, means located at opposite ends of the writing table adapted to engage the paper through registering apertures to arrest its progress and draw the intermediate portion of the paper tautly over the writing table, and means for releasing said means from its paper engagement.

5. In a manifolding machine comprising a suitable frame from which strips of paper are withdrawn, the combination with a writing table over which said paper passes longitudinally, of vertically disposed depressible and laterally movable pins that engage said paper, tension means for said pins drawing the paper, when the pins are engaged therewith, counter to its withdrawal direction of travel, and means for moving said pins below the plane of the table.

6. A manifolding machine comprising a suitable casing inclosing a strip of paper having a longitudinally disposed series of equi-distant alining perforations, in combination with a device situated at the front end of the casing carrying members alined with the perforations to enter said perforations *seriatim*, and a device at the rear end of the casing carrying members alined with the perforations to enter said perforation *seriatim* and mounted to move with the paper, tension means therefor, and means for withdrawing both of said devices from said perforations.

7. In a manifolding machine comprising a casing from which strips of paper are withdrawn, a platen over which the paper passes, the paper having apertures spaced longitudinally, and vertically disposed pins at the rear end of the platen, each yieldingly urged toward the paper to act thereon and engage in the apertures in the paper as they come in registration with the pins and yieldingly urged in a direction counter to the travel of the paper for exerting a rearward pull upon the paper when engaged with said pins.

8. In a manifolding machine comprising a casing from which strips of paper are withdrawn, a platen over which the paper passes, the paper having apertures spaced longitudinally, means at the forward end of the platen to engage the paper, and vertically disposed pins at the rear end of the platen, each yieldingly urged toward the paper to act thereon and engage in the apertures in the paper as they come in registration with the pins and yieldingly urged in a direction counter to the travel of the paper

for exerting a rearward pull upon the paper when engaged with said pins.

9. In a manifolding machine a suitable frame work from which strips of paper are withdrawn the combination with a platen over which said paper passes longitudinally from the rear, of means located at the forward end of said platen to engage the paper, vertically disposed depressible and transversely movable pins located at the rearward end of said platen to engage said paper to move under tension with the paper when engaged, tension means for said pins, and means for moving said pins downward below the plane of said platen.

10. A manifolding machine comprising a frame including a writing table over which strips of paper pass longitudinally, means for engaging the paper at the forward end of the writing table, and yielding means for engaging the paper at the rearward end of the writing table for drawing that part of the paper between said paper engaging means taut over the writing table.

11. In a manifolding machine, a frame including a platen over which strips of paper pass longitudinally from the rear, vertically disposed depressible pins located at the forward end of said platen to engage said paper, vertically depressible and transversely movable pins spaced from said first named pins to engage the paper, and movable with the paper when engaged, and tension means for said pins for exerting a force counter to the direction of paper motion for drawing the paper taut between said pins when engaged thereby.

12. In a manifolding machine, a frame in-

cluding a platen over which strips of paper pass longitudinally from the rear, vertically disposed depressible pins located at the forward end of said platen to engage said paper, vertically depressible and transversely movable pins spaced from said first named pins to engage the paper, and movable with the paper when engaged, tension means for said pins for exerting a force in a direction counter to the direction of paper motion for drawing the paper taut between said pins when engaged thereby and means for moving both sets of pins downward below the plane of said platen.

13. In a manifolding machine, a frame including a platen over which strips of paper pass longitudinally from the rear, vertically disposed depressible pins located at the forward end of said platen to engage said paper, vertically depressible and transversely movable pins spaced from said first named pins to engage the paper, and movable with the paper when engaged, tension means for said pins for exerting a force in a direction counter to the direction of paper motion for drawing the paper taut between said pins when engaged thereby and a device connecting with said forward and rear pins for moving the same in unison below the plane of said platen to free them of their paper engagement.

In testimony whereof, I hereunto subscribe my name, as attested by the two subscribing witnesses.

ALBERT KRAUTH.
